UNITED STATES PATENT OFFICE.

MARTINIANO FLORO, OF CHAMPAIGN, ILLINOIS.

VOTING MACHINE.

1,425,955.

Specification of Letters Patent. Patented Aug. 15, 1922.

Application filed April 18, 1921. Serial No. 462,223.

To all whom it may concern:

Be it known that I, MARTINIANO FLORO, a citizen of the United States, residing at Champaign, in the county of Champaign and State of Illinois, have invented certain new and useful Improvements in Voting Machines, of which the following is a specification.

This invention relates to voting machines, and it comprises a casing, a plurality of counters or registering machines arranged in said casing, levers connected thereto, said levers being provided with means for arranging suitable indicia thereon to identify 10 different candidates, means for retaining said lever in withdrawn position after voting to prevent duplicate voting, means for returning said lever to operative position, and means for locking said levers to prevent 15 unauthorized voting.

In the present invention, I have provided a voting machine which eliminates the necessity of writing ballots and counting them after the votes have been cast. The names 20 and pictures of the candidates, or other suitable indicia, are arranged on suitable levers connected to individual counters or registering machines, and when the voter presses the lever, the vote is registered. The voting machine is adapted to be arranged in 25 a booth or other container, and an electric circuit is provided which is normally open, but will be closed upon the closing of the door of the booth, or in other similar manner, and will remain closed while the voter 30 is in the booth. When a lever is depressed to register a vote, a circuit is closed through an electro-magnet arranged adjacent said lever, and the lever is retained in withdrawn 35 position until the circuit is opened when the voter leaves the booth. It is, therefore, impossible for a voter to cast more than one vote 40 for a single candidate.

After the voting has been completed, and 45 before the machine is opened to show the result, the levers may be locked in inoperative position to prevent unauthorized voting for any candidate.

In the accompanying drawings, I have 50 shown one embodiment of the invention. In this showing:

Figure 1 is a perspective view of the machine,

Figure 2 is a front elevation with a portion of the front plate removed,

Figure 3 is a transverse vertical sectional view of the machine,

Figure 4 is a plan view with the cover in open position and the top plate partially removed, and,

Figure 5 is a diagrammatic view of the electric circuits.

Referring to the drawings, the reference numeral 1 designates a box or receptacle provided with a hinged cover 2, and a hinged plate 3. Suitable handles 4 may be arranged on the ends of the box for the purpose of transportation. A top plate 5 is arranged within the box, the plate being adapted to be received in grooves or recesses 6 in the side and end walls of the box. When the front plate is in closed position, the top plate is retained in position and cannot be removed until the front plate is opened. As shown, the front plate may be retained in 75 closed position by means of a lock 6.

A suitable shelf or bracket 7 is arranged within the box adapted to receive and support a plurality of vertical standards or yokes 8. Levers 9 are pivotally supported 80 in said yokes or standards. These levers are provided with openings near one end, having pins 10 arranged therein and adapted to receive the forked end 11 of an operating rod 12. The operating rod is provided with 85 an enlarged head 13, on which suitable indicia 14 indicating different candidates may be arranged. As shown, the top plate is provided with openings 15 arranged over the heads of the operating rods. The pivoted lever 9 is provided with a link 16, connected to a lever 17, arranged on a counter 18. As shown, a plate 19 is arranged in front of the counters, and this plate is provided with a plurality of openings 20, to 90 permit reading of the counters from the front. A glass plate 21 may be arranged between the plate 19 and the front plate 3.

The pivoted lever 9 is provided with a plate 22, of soft iron or other suitable material adapted to be attracted by an electro-magnet 23 when the magnet is energized. A coil spring 24 is attached to the lever and to the shelf or bracket 7 to retain the lever in the full line position when the magnet is deenergized. A copper rod 25 extends longitudinally of the casing at the rear, being supported in suitable brackets 26. One of these brackets is provided with a binding post 27, adapted to be connected to a lead 110

wire 28. The electro-magnet 23 is connected to a lead wire 29, and when the lever is depressed to the dotted line position, a circuit is completed through the copper rod 25, the lever 9, the post or standard 8, and thence through the magnet by a connection 30 between the post or standard and the magnet.

Referring to Figure 5 of the drawings wherein the circuit is diagrammatically illustrated, the wires 28 and 29 are connected to a source of current 31. A switch 32 is arranged in one of the connections, and this switch may be connected to the door of a booth (not shown), in which the voting machine is arranged so that the circuit will be closed when the voter enters the booth and will remain closed until he leaves. If the machine is not arranged in a booth, the switch 32 may be operated by the supervisor of elections or other official to maintain a closed circuit while each voter is casting his vote. The wires 28 and 29 may be connected by a branch wire 33, having a lamp or other signal 34 arranged therein, which may be positioned on the outside of the booth to enable the supervisor of elections to see that the circuit remains closed while the voter is in the booth.

Means are provided for locking the machine after the votes have been cast. As shown, a rod or shaft 35 is supported in suitable brackets 36, and this rod is provided with a plurality of blocks or locking members 37. When the block or locking member is in the full line position shown in Figure 3 of the drawings, the pivoted lever 9 is free to operate, but when turned at right angles to arrange its major axis in a vertical plane, it engages the lever and retains it in inoperative position. A lock 38 may be arranged in one of the side walls of the casing to permit operation of the locking members.

The operating rods 12 may be provided with enlargements or collars 39 which are adapted to engage a plate 40, arranged below the top plate 5 to limit the upward movement of the levers.

In operation, the circuit is normally open when the voter enters the booth, and the levers are in the full line position shown in Figure 3 of the drawings. When the voter enters the booth, the circuit is closed, by switch 32, and the lamp 34 is lighted. This lamp should remain lighted the entire time the voter is in the booth to indicate that the circuit has not been broken. The lamp is preferably arranged on the outside of the booth where it may be seen by the election officers and other persons. To vote for candidates for the different offices, it is merely necessary for the voter to depress the pivoted levers 9, bearing the name or other indicia of the officer by applying suitable pressure 65 with the finger or other instrument to the en-

larged head 13 of the lever 12. Through the connections 16 and 17, the vote is registered on the counter 18. When the lever 9 is moved on its pivot in the voting operation, it engages the copper rod 25 to close the circuit and energize the magnet. The magnet then attracts the iron plate 22, secured to the lever, and the lever is retained in inoperative position shown in dotted lines. It will be apparent that as long as the circuit 70 remains closed, the levers will remain in inoperative position and it is therefore, impossible to cast more than one vote for a given candidate. As the voter leaves the booth and the switch 32 is opened, the magnet is deenergized and the spring 24 returns the lever to operative position. The strength of the spring 24 should be calculated to be sufficient to return the lever to operative position but insufficient to overcome the attraction of the magnet for the iron plate 22.

When the voters have cast their ballots, the machine may be locked in inoperative position by means of the locking rod 35, and the locking members 37. The machine 90 is then carried to the officer designated to count the votes, and the front plate 3 is opened by unlocking lock 6. The total may then be immediately ascertained without the necessity of counting individual ballots.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A voting machine comprising a counter, an operating lever connected to said counter, an electro-magnet arranged adjacent said lever and adapted to retain it in inoperative position when the magnet is energized, a rod connected to a source of current, means for completing a circuit through said magnet, and connecting means between said rod and said magnet to energize said magnet when the lever is depressed.

2. A voting machine comprising a counter, a lever connected to said counter, an electro-magnet arranged adjacent said lever and adapted to retain it in inoperative position when the magnet is energized, an electric conductor connected to a source of current, means for establishing a circuit from said conductor through the electro-magnet when the lever is operated, remote means for opening said circuit, and means for returning said lever to operative position when the circuit is opened.

3. A voting machine comprising a counter, an operating lever connected to said counter, an electro-magnet arranged adjacent said

lever, an electric conductor arranged adjacent said magnet, means for establishing a circuit through said magnet when the lever is operated to retain the lever in inoperative position, means for opening said circuit to de-energize the magnet, and a spring to return the lever to normal position when the magnet is deenergized.

4. A voting machine comprising a casing, 10 a counter arranged therein, a pivoted lever arranged in said casing, an operating rod connected to said lever and terminating adjacent the top of the casing, a top plate arranged above the upper ends of said levers, 15 said plate being provided with an opening to permit depression of said operating rod, an operating connection between said lever and said counter to register each actuation of the lever, an electro-magnet arranged adjacent said lever and adapted to retain the lever in inoperative position when energized, and means for energizing said magnet upon actuation of said lever.

5. A voting machine comprising a casing, 20 a counter arranged in said casing, a pivoted lever arranged in said casing and connected with said counter to register each actuation of the lever, an operating rod connected to said pivoted lever, said operating rod ter-

minating adjacent the top of the casing, a 30 top plate arranged over said lever, said plate being provided with an opening arranged above said operating rod, an electro-magnet arranged adjacent said lever and adapted to retain the lever in inoperative 35 position when energized, an electric conductor arranged in said casing, said conductor being adapted to engage said pivoted lever upon actuation thereof, means for establishing a circuit from said pivoted lever 40 through the electro-magnet, remote means for opening said circuit, and a spring to return said pivoted lever to normal position when the magnet is deenergized.

6. A voting machine comprising a counter, 45 an operating lever connected to said counter, an electro-magnet arranged adjacent said lever, means for completing a circuit through said magnet when the lever is operated to retain the lever in inoperative position, and 50 remote means for opening said circuit.

In testimony whereof I affix my signature in presence of two witnesses.

MARTINIANO FLORO.
